DESIGN FOR A COMBINATION SCREW DRIVER AND CAP AND LID REMOVER

John B. Smiley, New York, N. Y.

Application February 4, 1941, Serial No. 98,734

Term of patent 14 years

To all whom it may concern:

Be it known that I, John B. Smiley, a citizen of the United States, residing at New York, in the county of New York and State of New York, have invented a new, original, and ornamental Design for a Combination Screw Driver and Cap and Lid Remover, of which the following is a specification, reference being had to the accompanying drawing, forming part thereof, in which:

Fig. 1 is a top plan view of a combination screw driver and cap and lid remover, showing my new design;

Fig. 2 is a bottom plan view thereof;
Fig. 3 is a side elevational view thereof; and,
Fig. 4 is an end elevational view thereof, taken from the left side of Fig. 3.

I claim:

The ornamental design for a combination screw driver and cap and lid remover, substantially as shown.

JOHN B. SMILEY.
